UNITED STATES PATENT OFFICE.

RICHARD D. GALLAGHER AND CHARLES DOUGLAS, OF DETROIT,
MICHIGAN; SAID GALLAGHER ASSIGNOR TO SAID DOUGLAS.

BROOM.

SPECIFICATION forming part of Letters Patent No. 232,958, dated October 5, 1880.

Application filed November 24, 1879.

To all whom it may concern:

Be it known that we, RICHARD D. GALLAGHER and CHARLES DOUGLAS, both of Detroit, in the county of Wayne and State of Michigan, have invented a new and useful Improvement in Brooms and Whisk-Brooms, which improvement is fully set forth in the following specification and accompanying drawings, in which—

10 Figure I is perspective view with a part of the broom cut away. Figs. II and III are longitudinal central sections.

The object of our invention is to facilitate the manufacture of brooms, so that they can 15 be made more perfectly and quickly with less stock, and to dispense with the skilled labor now required in the manufacture of the ordinary brooms.

In making these brooms the corn or fiber must 20 be first prepared in uniform lengths by disconnecting the fibers from the stalk and even- ing them from the brush or fine ends, and cutting from the butt-ends what is necessary to make them of even length, so that when the 25 broom is made it will not be necessary to cut off or trim any of the brush or fine ends of the broom-corn, which has to be done in finishing the ordinary brooms that are now made, and which is detrimental to their wearing 30 qualities.

The face *e* of the head *A* is provided with a series of longitudinal serrations, *S*, into which, after the broom-corn has been dampened and arranged on the face *e*, the butts are pressed 35 by means of the wooden clamp *B*, the latter

being securely held in place on the butts and head by the staples *c c*, straddling the clamp *B* near its ends, and having their hooked and pointed ends driven into the sides of the head *A*. The broom-corn is then bent into a perpendicular position, and the end wires, *F F*, are secured to the clamps *B* and head *A*, to prevent lateral movement of the broom-straws, and a continuous piece of leather, *a*, or fibrous material, is secured to the clamp *B* and head *A*, covering the space between them.

The lower end of the handle *D* is screw-threaded and screwed into a screw-threaded hole in the head *A* made to receive it.

We are aware that it is not new to clamp 50 the butt-ends of broom-straws between the head of a broom and a clamping-block secured to the head by bolts and nuts, and we therefore lay no claim, broadly, to such invention.

What we claim as our invention, and desire 55 to secure by Letters Patent, is—

The combination, with a series of broom-straws having their butts in juxtaposition, of the head *A*, clamping-block *B*, staples *c*, straddling said clamping-block and having their hooked ends secured to the head *A*, and end wires, *F*, substantially as described, and for the purpose set forth.

RICHARD D. GALLAGHER.
CHARLES DOUGLAS.
